UNITED STATES PATENT OFFICE.

WALLACE A. HOUTS, OF OAKLAND, CALIFORNIA.

TILE-MAKING MACHINE.

SPECIFICATION forming part of Letters Patent No. 737,843, dated September 1, 1903.

Application filed November 18, 1902. Serial No. 131,881. (No model.)

To all whom it may concern:

Be it known that I, WALLACE A. HOUTS, a citizen of the United States, residing in Oakland, county of Alameda, State of California, have invented an Improvement in Tile-Making Machines; and I hereby declare the following to be a full, clear, and exact description of the same.

My invention relates to improvements in machines for manufacturing drain-tiles, conduit-sections, and the like. Its object is particularly to provide an apparatus suitable for the manufacture of pipe or tiling from compositions containing asphaltum, sand, and the like.

It consists of the parts and the construction and combination of parts, as hereinafter more fully described, having reference to the accompanying drawings, in which—

20 Figure 1 is a general elevation of my invention. Fig. 2 is a partial plan view of same. Fig. 3 is a bottom view of ring with guide projections. Fig. 4 is a cross-section of same. Fig. 5 is a cross-section of cylindrical base-piece. Fig. 6 is a transverse section of mold and its elements. Fig. 7 is a segmental disk for insertion to form T's. Fig. 8 is a view of mold and attachments.

25 A represents the framework supporting the various parts of my apparatus. This frame is preferably constructed of angle and channel iron and properly braced, so as to withstand the heavy usage that it will naturally be subjected to. Suitably journaled in this frame is a vertical shaft 2, supporting a table 3 and rotated by any approved means, as the worm-gear 4, for it is desired that the table should have a slow movement and capable of being stopped instantly. The edge of 30 the table is supported upon rollers 5, running on a suitable track or support secured to frame A. Upon the table are disposed one or more molds constructed as follows: 6 is a cylindrical base-piece having inner and outer concentric walls connected at the bottom at intervals to form an annular box or socket. A ring 7 is movable in the space 8 between these walls. This ring has a series of guide projections 9, extending down through the holes in the bottom of space 8, and certain of these projections carry rollers 10 for the purpose to be described later. A plunger-core

11, having a conical upper end 12, is reciprocable centrally through the base-piece 6. The movement of the plunger downward is limited by a suitable stop, as 13, carried by the table and engaging the lower end of the core. It is not intended that the core should drop below a point where the base of the conical tip 12 shall be lower than the upper edge of the inner contiguous wall 14 of base-piece 6. When the core is thus depressed, the base-piece is designed to hold just sufficient material to make a tile.

20 In operation, assuming the core to be in its lowest position and ring 7 seated in the bottom of the annular space 8, the pocket is filled flush with the table. The material used is preferably a mixture of asphaltum, sand, and other ingredients previously rendered plastic by heat and having the quality when cooled of setting into a hard resistant mass. Suspended above each base-piece is a cylinder 15, adapted to fit within the upper end of the base-piece 6 and to form an annular space 75 (corresponding to the exact thickness and shape of the finished tile) between its inner surface and the core when the latter is projected up through the base-piece to its full limit. The lower end of the cylinder is formed 80 with an annular shoulder 16, corresponding to the upper beveled edge of 14. The part 14 is for the purpose of forming the flange of the tile. The cylinder 15 is movable between the vertical guides 17, carried on the table, 85 and is suspended by ropes 18, passing over these guides and having counterweights 19 on their other ends by which the raising and lowering of the cylinder may be facilitated. When the base-piece 6 has been filled with 90 the hot plastic material, as above described, the cylinder 15 is lowered until the flanges 20 on the outside of the cylinder rest on the table. These flanges are then engaged by the dogs 21 to prevent the cylinder from being 95 lifted when the core is reciprocated upward. The insertion of the cylinder into the mass within the base-piece and the subsequent action of lifting the core causes the material to fill all the space intervening between the 100 core and the cylinder. The lifting of the core and the compression of the tile is effected by means of the hydraulic presses 22 23, disposed one above and one below the table in the

plane of the path of the molds. On filling a base-piece the table is moved to bring the base-piece immediately above press 23 and beneath press 22. Press 23 is then operated to lift the plunger-core 11 till it projects above cylinder 15. A ring 25 is then inserted from the top between the core and cylinder 15, and the conical cap-plunger 26 of press 22 is operated to force the ring down to compress the material and give permanent form to the tile. The pressure on 25 continues until the point of core 11 projects up into the cap 26. In this latter upward movement of the core the ends of the projections 9 are engaged by the plunger of press 23 to lift the ring 7 and compress the flange end of the tile against the downward pressure of ring 25. Press 22 is then released, the dogs 21 turned to free flanges 20, and upon a further upward movement by press 23 ring 7, the tile, the core, and cylinder 15 are lifted a couple of inches. This serves to free the flange of the tile from wall 14 of the base-piece. The dogs 21 are then turned to interpose a stop to the return of the cylinder to its original position in the base-piece, press 23 is partially released, plate 27 is turned across the opening of cap-plunger 26, and press 22 is operated to push core 11 downward and free it from the tile. The continued downward movement of the plunger of press 22 causes ring 25 to be engaged and moved to free the tile from cylinder 15. If desired, the latter may be made with a slight taper on the inside, as shown, so that at the end of the last described movement a space will be left between the tile and the cylinder through which water may percolate and cool the tile. It will be noted that the tile has now been freed successively from the base-piece, the core, and the cylinder, and the core on leaving press 23 is free to fall by gravity to its first position of rest on stop 13. The table is then rotated to bring a succeeding base-piece into position between the presses, and the operation above described is repeated.

While I have shown but two base-pieces for purposes of illustration, there would as a rule be four or more base-pieces mounted upon the one table, giving a consequent increased capacity to the machine.

During the rotation of the table over the cam-guides 28 (by which latter the rollers 10 on the projections 9 are engaged to lift ring 7 and discharge the tile from the base-piece) the ring 25 and cylinder 15 are lifted out of engagement with the tile and a stream of water played upon the tile to cool it and cause it to set, so it may be handled subsequently without fear or likelihood of damage. Before passing from the guides 28 the tile is removed from the table, and on leaving said guides ring 7 falls back again into position in the bottom of base-piece 6.

If it is desired to make a tile to receive a lateral branch after the manner of a T, a concaved segment 29, of a diameter equal to

the outside diameter of said branch and of a thickness equal to the space between 11 and 15, may be inserted into the mass of material between 11 and 15 before ring 25 is put in place. After the tile is completed the part 29 can be knocked out, leaving a hole to receive the branch section.

Having thus described my invention, what I claim, and desire to secure by Letters Patent, is—

1. A tile-making machine including a movable support; a reciprocable core; mold-sections slidable relative to the core; and means in the path of said sections by which the sections may be actuated from above and below said support.

2. The combination in a tile-making machine of a movable support; a cylinder; a reciprocable core; mold-sections slidable relative to the core; and stationary presses disposed in line one above and one below said support in the plane of the path of the sections, for actuating the latter.

3. The combination in a tile-making machine, of a rotatable support, molds carried by said support, said molds including a stationary base-piece, a reciprocable core, a containing-cylinder and follower-rings operable between said core and cylinder.

4. The combination in a tile-making machine, of a rotatable support, molds carried thereby, said molds including a stationary base-piece, a reciprocable core, an inclosing cylinder for the core between which and the core the tile is formed, and end compression-rings.

5. The combination in a tile-making machine of a rotatable support, molds carried thereby, said molds including a stationary base-piece having concentric walls between which a containing-space is formed, a core reciprocable through said base-piece, a cylinder inclosing said core and between which and the core a tile-space is formed, end compression-rings and means disposed in the plane of the path of said molds by which the latter are operated.

6. The combination in a tile-making machine of a rotatable support, molds carried thereby, said molds including a stationary base-piece having concentric walls between which a containing-space is formed, a core reciprocable through said base-piece, and a removable cylinder adapted to fit said base-piece and inclose the core.

7. In a tile-making machine a mold including a stationary base-piece, a reciprocable core, a removable cylinder fitting said base-piece and co-operating with the latter and the core to inclose a tile-space, end compression-rings and means by which said core, cylinder and rings may be suitably operated.

8. The combination in a tile-making machine of a rotatable support, molds carried thereby, said molds including a stationary base-piece having concentric walls between which a containing-space is formed, a core re-

- ciprocable through said base-piece, a removable cylinder fitting the latter and coöperating with the same and with the core to form a tile-space, end compression-rings movable at either end of said tile-space and stationary presses disposed in line one above and one below said support in the plane of the path of said molds whereby said end compression-rings and core are reciprocated.
9. The combination in a tile-making machine of a rotatable support, molds carried thereby, said molds including a stationary base-piece having concentric walls between which a containing-space is formed, the bottom of said space perforated, a ring seating in said space having projections extending through said perforations, a reciprocable core, an inclosing removable cylinder between which and the core a tile-space is formed, a removable ring fitting said space and means by which said movable parts are operated.
10. The combination in a tile-making machine of a rotatable support, molds carried thereby, said molds including a stationary base-piece having an annular containing-space, a reciprocable core operable from below, stop means carried by the support for limiting the downward movement of said core, a ring movable in the annular space inclosed within said base-piece, a removable cylinder coöperating therewith and with said core to
- form a tile-space, a removable ring fitting the upper end of said tile-space and means for actuating the several movable parts.
11. The combination in a tile-making machine, of a rotatable support, molds carried thereby, said molds including a stationary base-piece having concentric walls between which a containing-space is formed, the bottom of said space having perforations, a ring seating in said space and having projections extending through said perforations, cam-guides in the path of said projections, a core reciprocable through said base-piece and having a conical tip, a counterbalanced cylinder adapted to inclose the core, a ring fitting between said core and cylinder, stationary presses disposed in line and in the plane of the path of said molds by which pressure may be exerted on said core and rings to compress the material, the upper press having a conical plunger-head conformable to the conical tip of the plunger and a turnable plate carried by said plunger-head for the purpose described.
- In witness whereof I have hereunto set my hand.
